UNITED STATES PATENT OFFICE.

JAMES A. MORE AND LEWIS GRUBE, OF LOWER SAUCON, PENNSYLVANIA.

SLED-BRAKE.

SPECIFICATION forming part of Letters Patent No. 250,566, dated December 6, 1881.

Application filed September 12, 1881. (No model.)

To all whom it may concern:

Be it known that we, JAMES A. MORE and LEWIS GRUBE, citizens of the United States of America, residing at Lower Saucon, in the county of Northampton and State of Pennsylvania, have invented certain new and useful Improvements in Sled or Sleigh Brakes; and we do hereby declare the following to be a full, clear, and exact description of the invention, such as will 10 enable others skilled in the art to which it app pertains to make and use the same, reference being had to the accompanying drawings, and to letters or figures of reference marked thereon, which form a part of this specification.

15 Our invention relates to automatic sled-brakes; and it consists in the construction and arrangement of its several parts, as will be hereinafter fully explained.

The accompanying drawings fully illustrate 20 our invention, Figure 1 being a side view, and Fig. 2 a plan of the same.

A is a sled of ordinary construction, having runners a , stanchions a' , cross-braces a^2 , and side braces, a^3 , as shown.

25 B is the tongue. It passes through a hole in the forward brace, and its inner end enters a slot in the second brace. It has pivoted to it the inner end of the brake-lever b , which is also pivoted to the bar b' , and has pivoted to its outer 30 end the connecting-rod c , as shown.

Hinged to the back brace, a^2 , is the brake-bar d , having rods d' , to which are pivoted the horizontal brake-pins e , which may pass through runners or be held by suitable means 35 upon their ends or sides, as shown.

To either end of the brake-bar d is secured

the crank f , which has pivoted to it the connecting-rod c , as shown.

g is the brake-stop. It passes through a hole in the side brace, a^3 , rests on a hanger placed 40 on the forward brace, a^2 , as shown, and prevents the automatic action of the brake, when desired.

To render the brake operative it is necessary 45 only to withdraw the brake-stop from the recess.

In the operation of my brake it will be seen that when the sled descends a hill the resistance of the tongue forces it backward, carrying with it the brake-lever b , connecting-rod 50 c , crank f , and brake-bar d , which operates to force the brake-pins e down into the snow and stop or impede the sled.

We do not confine ourselves to the application 55 and operation of the device upon one side of the sled, but provide that when heavy grades are encountered or heavy loads hauled the operating device may be placed upon both sides, the brake-levers b crossing each other under the tongue B.

60 What we claim is—

In a sled-brake, the lever b , pivoted to the lug b' , secured to the brace a^2 , operating, in combination with the tongue B and stop g , substantially as shown and described.

65 In testimony whereof we affix our signatures in presence of two witnesses.

JAMES A. MORE.
LEWIS GRUBE.
